(57) **CLAIM**

The ornamental design for an awning, as shown and described.

DESCRIPTION

FIG. 1 is a front, left, top-side perspective view of the awning showing our new design;

FIG. 2 is a top view thereof;

FIG. 3 is a bottom view thereof;

FIG. 4 is a front view thereof;

FIG. 5 is a back view thereof;

FIG. 6 is an enlarged right-side view thereof; and,

FIG. 7 is an enlarged left-side view thereof.

The broken lines in the drawings depict portions of the awning that form no part of the claimed design.

1 Claim, 7 Drawing Sheets
